UNITED STATES PATENT OFFICE

CHARLES W. MABEY, OF INDIANAPOLIS, INDIANA.

FOREHEAD-BAND.

No. 854,509.

Specification of Letters Patent.

Patented May 21, 1907.

Application filed July 20, 1906. Serial No. 327,009.

To all whom it may concern:

Be it known that I, CHARLES W. MABEY, a citizen of the United States, and a resident of Indianapolis, in the county of Marion and 5 State of Indiana, have invented a new and Improved Forehead-Band, of which the following is a full, clear, and exact description.

My invention has for its object to provide means adapted to relieve a person of headache 10 and insomnia. This I accomplish by the means illustrated in the accompanying drawings, in which drawings like characters of reference indicate like parts throughout the views, and in which

15 Figure 1 is a perspective view of a device embodying my invention applied to the head of a user; Fig. 2 is a perspective view partly broken away of a device embodying my invention; and Fig. 3 is a transverse section 20 taken on the line 3—3 of Fig. 2.

As illustrated in the drawings, 1 represents a metallic band constructed of flexible metal, adapted to be curved longitudinally so as to conform to the shape of the forehead of a person. 25 The ends 2 of the band are inclined downwardly and the inner surface of such ends is formed with a convex projection 3 adapted to be pressed against the temples of the user. These ends of the band are 30 preferably made concavo-convex in cross section, as indicated in Fig. 3. An elastic cord 5 is connected with the convex ends 3 of the band. The band is covered by an absorbent material 4 which may consist of a 35 textile fabric or other material adapted to absorb and retain chemical mixtures adapted to aid in relieving headache or insomnia. When the device is applied to the forehead of a user the soft flexible nature of the metallic band 1 permits the band to conform to 40 the contour of the user's forehead, while the downwardly extending arms 2 with the convex projections 3 bear against the temples of such user, and all the parts are held in place 45 with gentle pressure by means of the elastic cord or band 5 extending around the back of the user's head.

The covering material 4 may be saturated with chemicals of a character suitable to relieve headache or insomnia, and such 50 chemicals are by means of such device adapted to be drawn from the covering material by the heat of the forehead of the wearer. The simplicity of the construction of this band enables one to wear the same with a 55 hat on, in any place, or at any time without inconvenience.

Having thus described my invention, what I claim as new and desire to secure by Letters Patent is:

1. The combination of a metallic band enclosed within a covering of absorbent material and provided with off-set ends having convex extremities, and an elastic band secured thereto at its ends adapted to hold said 65 metallic band against the forehead of a user by elastic tension, substantially as shown and described.

2. A forehead band comprising a longitudinal metallic plate having angularly depending ends and an elastic band secured to said ends, adapted to exert an elastic pressure on the side of said forehead plate and to encircle the head of a user in a plane below the central longitudinal plane of said plate, 75 substantially as shown and described.

3. A head band comprising a forehead plate consisting of a longitudinal band covered with absorbent material, and provided with ends extending at an angle to the longitudinal line of said plate, and a band connected 80 with said ends and adapted to encircle the head of a user in a plane below the central longitudinal line of said plate.

In testimony whereof I have signed my 85 name to this specification in the presence of two subscribing witnesses.

CHARLES W. MABEY.
